(57) **CLAIM**

The ornamental design for an electrophoretic gel comb, as shown and described.

DESCRIPTION

FIG. 1 is a perspective view of an electrophoretic gel comb according to a first embodiment of the present invention; FIG. 2 is a front view of the electrophoretic gel comb of FIG. 1;

FIG. 3 is a rear view of the electrophoretic gel comb of FIG. 1;

FIG. 4 is a right side view of the electrophoretic gel comb of FIG. 1;

FIG. 5 is a left side view of the electrophoretic gel comb of FIG. 1;

FIG. 6 is a top view of the electrophoretic gel comb of FIG. 1;

FIG. 7 is a bottom view of the electrophoretic gel comb of FIG. 1;

FIG. 8 is a perspective view of an electrophoretic gel comb according to a second embodiment of the present invention; FIG. 9 is a front view of the electrophoretic gel comb of FIG. 8;

FIG. 10 is a rear view of the electrophoretic gel comb of FIG. 8;

FIG. 11 is a right side view of the electrophoretic gel comb of FIG. 8;

FIG. 12 is a left side view of the electrophoretic gel comb of FIG. 8;

FIG. 13 is a top view of the electrophoretic gel comb of FIG. 8; and,

FIG. 14 is a bottom view of the electrophoretic gel comb of FIG. 8.

Any portions shown using dashed lines are for illustrative purposes only and form no part of the claimed design.
